UNITED STATES PATENT OFFICE.

WILLIAM E. SMILEY, OF CAZENOVIA, AND HOWARD D. GA NUNG, OF SYRACUSE, NEW YORK; SAID GA NUNG ASSIGNOR TO SAID SMILEY.

PINCH BAR.

Application filed July 24, 1922. Serial No. 577,234.

To all whom it may concern:

Be it known that we, WILLIAM E. SMILEY and HOWARD D. GA NUNG, citizens of the United States, residing, respectively, at 5 Cazenovia, in the county of Madison and State of New York, and at Syracuse, in the county of Onondaga and State of New York, have invented certain new and useful Improvements in Pinch Bars, of which the 10 following is a specification.

This invention relates to improvements in pinch-bars, designed especially for moving cars and the like, and has for its object to provide a device of the class consisting 15 of a main lever which is operated manually, and an auxiliary lever which pivotally supports and serves as a fulcrum for the main lever. A further object is to provide a two-part corrugated fulcrum, which is adjustably applied to the auxiliary lever, the said 20 fulcrum having radial teeth which bite into the lateral margins of the rail, for preventing the bar from slipping during the car-moving operations. A further object is to 25 provide novel and simple means for adjusting and setting the two parts of the fulcrum, so that the point of contact with the rail is located in advance of the center at 30 which the pinching force is applied for preventing the bar from backing away from the wheel. The said fulcrum parts also being independently adjustable for bringing sharp and unworn teeth into engagement with the rail. A further object is to provide 35 a pinch-bar which may be disposed beneath a car wheel and left there for preventing accidental movement of the car. And a further object is to provide means for limiting the downward movement of 40 the main lever for preventing injury to the operator.

This invention relates particularly to improvements in the pinch-bar shown and described in U. S. Patent #1,329,436 dated 45 Feb. 3, 1920.

The various features and parts will be understood from the detailed description which follows, and by reference to the accompanying drawing, in which—

50 Figure 1 is a side view of the improved pinch-bar applied to a car wheel ready to be operated. Fig. 2 is a similar view; showing the main lever and detachable handle depressed. Fig. 3 is a broken top plan view

of the device. Fig. 4 is a central vertical 55 longitudinal section, taken on line 4—4 of Fig. 3. Fig. 5 is a vertical cross-section, taken on line 5—5 of Fig. 3. Fig. 6 is an enlarged broken section; showing means for locking the corrugated fulcrum members in place. Fig. 7 is an inner face view of one of the fulcrum members. Fig. 8 is a broken 60 elevational view of the auxiliary lever. And Fig. 9 is a view showing a modification of the detachable and reversible fulcrum parts. 65

In the drawing, 2 represents a car wheel, and 3 represents an ordinary railroad rail.

Our improved pinch-bar consists of a main pinching member 4, and an auxiliary pinching member 5, the latter having a long 70 arm 5', and a short arm 5", and the said arms preferably being disposed at an angle to each other, as shown. The long arm 5' of member 5 comprises a fork, and its free end is perforated, to receive a bolt 4', 75 by which the member 4 is pivoted for movement vertically within the said fork. The opposite lateral sides of member 5 are provided with broken cone-shaped axially aligning sockets 5^b and 5^c, which face outwardly, 80 the bottom portions of said sockets being cut-away facing the rail 3. These sockets are arranged to receive the cone-shaped portions of similar corrugated fulcrum members 6 and 6', each having a number of regularly 85 spaced relatively sharp teeth 6^a, which engage and bite the lateral beaded margins 3' of the rail 3, as best seen in Figs. 4 and 5. The fulcrum members are each bored out axially to receive a common bolt or axle 90 6^b, which is shown held in place by a nut 6^c. The tightening up of the nut tends to draw the members 6—6' towards each other for tightly engaging the sockets 5^b—5^c. The inner end portions of the members 6—6' 95

comprise reduced cylinders 6^d, which are slightly spaced from each other for facilitating proper adjustment of the parts. The fulcrum members 6—6' are held from rotation when applied to the lever 5, by means 100 of inwardly facing teeth 5^a, which are disposed in the oposite sides of the sockets 5^b—5^c. The teeth 5^a, while holding the members 6—6' from rotation, as described, are especially provided for effecting the 105 similar registering of the said members, as best shown in Fig. 6, wherein but one tooth (indicated at x) of each member comes into

21 contact with the rail 3, when the bar is first chocked in the crotch formed by the wheel and the rail, as shown in Fig. 1. By this construction and arrangement, the 5 points of contact (*x*) between the members 6—6' and the rail 3, are located forwardly of the vertical axis of the fulcrum, as indicated by the broken line A in Fig. 6. The 10 importance of this last described feature will become apparent when it is understood that practically all of the older pinch-bars tend to slip away from the car wheels during the initial depressing movement, as of the handle or main member 4. This results 15 in considerable loss of power and time, and calls for many extra operations in order to move a car the desired distance. In the present device, by locating the point of contact (*x*) forwardly of the center A at which 20 the force is applied, the initial depressing movement of the pinch-bar swinging around the axis 6^b, tends to force the bar forwardly deeper into the crotch of the 25 wheel and rail, thereby preventing any loss of power or waste of time. After the handle, as 8, has been lowered a short distance, the adjacent teeth 6^a make contact with the rail 3 at *y* (see Fig. 6). The 30 continued depression of the handle, shifts the weight from the teeth at *x*, to the point *y*, while the center A swings rearwardly towards the latter point, corresponding to the 35 elevation of the shorter arm 5^a of the lever 5. The arm 5^a of the member 5 is provided with a flat bottom 3^a which lies firmly on the top face of the rail 3, and in order to 40 prevent the lateral movement thereof, the opposite sides of the said bottom are provided with drooping margins 5^e. The free 45 end of the arm 5^a represents the pinching nose 5^f. As the nose 5^f is liable to wear away after a few operations and thereby render said part unfit for pinching cars, we provide a detachable preferably highly tempered nose-piece 7, which is pivotally held in place by 50 a bolt 7^f, and a nut 7^a, the latter being disposed in a socket 7^b in the bottom 3^a (see Fig. 4). The rear edge of the nose-piece 7 preferably bears against a round shoulder 7^c of the member 5, and when the bar is 55 forced between the wheel and the rail, the forward edge of the part 7 readily conforms to the usual bevel face of the wheel's tread, by rotating slightly on the pivot 7^f, to the extent allowed by the curvature of the shoulder 7^c, as shown by full and dotted lines in Fig. 3. This construction and arrangement insures the full bearing of the 60 part 7 against the wheel, whether or not the latter bevels towards the right or left. By providing the two fulcrum members 6—6', either or both of said parts may be 65 frequently adjusted for bringing the unworn teeth 6^a into the contact positions shown at *x*—*y* in Fig. 6, by simply loosen-

ing the bolt 6^b. This prolongs the life of the members 6—6', without any loss of efficiency till the last tooth 6^a is worn out.

The pinching member 4 consists of a hollow tapering socket 4^a, which is arranged to 70 receive the tapering end 8' of the detachable handle 8, the latter preferably being held in the socket by friction. Beyond the socket 8' the member 4 is solid and is perforated to receive the bolt 4', by which said member 75 is pivoted in the forked arm 5' of the auxiliary member. Beyond the pivot 4' the member 4 is provided with a socket 4^b, in which is loosely journaled a roller 9, by a pin 9'. This roller preferably projects some distance 80 above the top-side of the lever 4, and is employed the same as the nose-piece 7, for engaging and moving the wheel 2, when the handle 8 is depressed. From the roller 9 the member 4 extends downwardly at an 85 angle, for providing a safety stop 10, the angularity of said stop being such that, its free end does not contact with the tread 90 of the wheel 2, until the member 4 and the roller 9 have completed the pinching operation. During the pinching operation the member 4 exerts its maximum lifting power 95 only while the roller 9 is in engagement with the tread of the wheel 2. The extent of this lifting power may be appreciated by comparing the distance between the pivots 4' and 9' with the length of the member 4 from the pivot 4' to the free end of the handle 8. Primarily, the safety stop 10 is 100 provided for preventing the sudden downward movement of the handle 8, at the end of each effective pinching stroke, and after the roller 9 is swung free by the forward movement of the wheel 2. In practice, the stop 10 makes contact with the wheel and 105 practically arrests the downward movement of the handle 8, when the latter reaches a point which varies from eight to twelve inches from the rail 3. This prevents injury to the operator's hands by the latter 110 striking against the rail. The extension 10 performs another function, viz., that of stopping the upward swing of the handle 8, by engaging the top surface of the barrels 6^d of the corrugated fulcrums, as shown 115 in Figs. 1, 4 and 5. By the latter provision, the device may be employed for blocking the wheel 2 against accidental movement by gravity or otherwise, during the loading and unloading of the car. When used as a block, the weight and pressure of the wheel is exerted against the nosepiece 7 and the roller 9, as shown in Fig. 1. During the blocking interval, the handle 8 should be withdrawn 120 from the socket 4^a, as a precaution against accident or tampering.

Figure 9 illustrates a modification of the device, wherein the auxiliary member 12 is provided with a plain pinching nose 12', and lateral angular sockets 12^a, which re- 130

ceive correspondingly shaped fulcrum members 13, the said members having similar relatively large angular teeth 13^a—13^b at the top and bottom sides. These fulcrum members are reversible for bringing the top-most teeth into engagement with the rail 3, and the said members as well as the members 6—6' are interchangeable. 14 represents the main pinching member which is similar to the member 4, except that the pinching portion 14' is a plain hump, instead of a roller (as 9). In all other respects the modified structure is substantially the same as that shown and described.

Having thus described our invention, what we claim, is—

1. A pinch bar for moving cars, including a manually operable pinching lever and an angular auxiliary pinching member, the said parts being pivotally connected, said lever and said member each having a pinching nose adapted to engage the tread of a car wheel, spaced fulcrum means carried by said member adapted to bite the opposite lateral margins of the rail, means for indexing and holding the fulcrum means for preventing the skidding of the pinch bar away from the car wheel while the pinching force is being applied, and means for adjusting the fulcrum means independently of each other.

2. In a pinch bar, a main pinching lever having a socket at one end and an angular stop at the other end, a portion of said lever intermediate its ends adapted to engage the tread of a car wheel, an auxiliary pinching member having a long arm for pivotally supporting said main lever and having a short arm whose free end comprises a pinching nose arranged at an angle to the longer arm, and having similar registering sockets disposed intermediate the free ends of said arms, similar fulcrum members having teeth for biting the rail adjustably disposed in the sockets of said auxiliary member, and means for rigidly holding said fulcrum members in said sockets.

3. In a pinch bar for moving cars, the combination of similar aligning fulcrum members, having a common axis the said members having corresponding radial teeth adapted to bite the lateral margins of a rail, an auxiliary pinching lever having lateral sockets to receive the said fulcrum members, means for adjusting said fulcrum members independently of each other, means for indexing said fulcrum members whereby one tooth of each member engages the rail at a point forwardly of the vertical axis of said fulcrum members at the start of the pinching operation, the next adjacent teeth being arranged to supplement the first teeth for preventing slippage of the bar during the final pinching stroke, a main lever adapted to be manually operated pivo-

tally supported by the rear end of said auxiliary lever, said main lever adapted to engage the tread of the car wheel, and a detachable and reversible nose-piece carried by the forward end of the auxiliary member 70 adapted to co-operate with said lever for moving the car.

4. The combination of similar axially aligning fulcrum members, said members having angular teeth adapted to bite the lateral margins of a rail, an auxiliary pinching member having laterally facing sockets to receive said fulcrum members, said sockets being provided with radial teeth adapted to position said fulcrum members so that one tooth of each member engages the rail at a point forwardly of the vertical axis of said sockets, a nose-piece adjustably mounted on the forward end of said auxiliary member, a main pinching member pivoted to the rear end of such auxiliary member the forward end of said main member being arranged at an angle and adapted to engage the tread of the car wheel for arresting the downward movement of the main member at the end of the pinching operations, and a roller pivoted at the apex of the angle of said main member adapted to co-operate with said nose-piece for pinching a car wheel.

5. A pinch-bar for moving railroad cars including an angular auxiliary pinching member, the forward end of said member comprising a pinching nose, the rear end of said member being forked, sockets formed in the opposite lateral sides of said auxiliary member and aligning axially, similar corrugated fulcrum members adjustably applied to said sockets, the teeth of said fulcrum members adapted to bite the lateral margins of a rail and one tooth of each fulcrum member arranged to engage the rail at a point forwardly of the vertical axis of said members and said sockets, for preventing the pinch-bar from slipping away from the car wheel during the initial pinching operation, means for locking said fulcrum members in said sockets for preventing rotation thereof, and a main lever pivoted in the fork of the auxiliary member, the forward end of said main lever comprising a stop adapted to engage the tread of the car-wheel limiting the downward movement of said lever, and said lever having an upwardly and forwardly projecting pinching portion beyond said stop adapted to co-operate with said pinching nose for moving the car.

6. A pinch-bar comprising an angular auxiliary pinching member, the forward end of said member comprising a pinching nose, the rear end of said member being forked, and the opposite sides of said member adjacent the apex of said angle being formed with similar conical sockets, corrugated cone-shaped fulcrum members disposed in said sockets and aligning axially, the corrugated

gated portions thereof being spaced substantially the breadth of the top face of a rail, means for holding said fulcrum members tightly in said sockets, means for indexing 5 said fulcrum members so that but one tooth of each fulcrum member engages the rail at a point forwardly of the vertical axis of said sockets at the start of each pinching operation, a main pinching member pivoted rearwardly of said sockets and having a hump 10 adapted to co-operate with said pinching nose for moving the car wheel.

7. In a pinch-bar the combination of a main lever and an auxiliary lever, said levers 15 being pivotally connected and adapted to be operated in a vertical plane, the forward end of said auxiliary member comprising a pinching nose adapted to engage the tread of a car wheel adjacent the rail, the main 20 lever having an upwardly projecting pinching portion near its forward end adapted

to engage the tread of the wheel at a higher plane, the opposite lateral sides of said auxiliary member being formed with cone-shaped sockets having a common transverse 25 axis said sockets being disposed between the said pinching-nose and said pinching portion, similar corrugated fulcrum members disposed in and conforming to said sockets the teeth of said members adapted to bite the 30 opposite lateral margins of the rail, and means for positioning said fulcrum members in such a manner that the corresponding teeth of said members engage the rail forwardly of the vertical axis of said members 35 for preventing retrograde movement of the bar during the pinching operations.

In testimony whereof we affix our signatures.

WILLIAM E. SMILEY.
HOWARD D. GANUNG.
